UNITED STATES PATENT OFFICE.

ROBERT JOHNSTON, OF HUNTSVILLE, ALABAMA.

IMPROVEMENT IN SANDALS.

Specification forming part of Letters Patent No. 122,525, dated January 9, 1872; antedated December 22, 1871.

To all whom it may concern:

Be it known that I, ROBERT JOHNSTON, of Huntsville, in the county of Madison and State of Alabama, have invented a new and Improved Detachable Sole and Heel Protector; and I do hereby declare that the following is a full, clear, and exact description thereof, which will enable others skilled in the art to make and use the same, reference being had to the accompanying drawing forming part of this specification.

Figure 1 represents a side view of my improved sole and heel protector. Fig. 2 is a plan or top view of the same.

Similar letters of reference indicate corresponding parts.

My invention relates to an auxiliary plate to be used during rainy weather to keep out moisture, and under an ordinary boot-sole. It is also made readily detachable, so as to be removed therefrom in fine weather. It consists in a plate of some elastic wood, as oak or hickory, cut, steamed, and bent, as herein-after described and subsequently claimed.

A B represent the auxiliary detachable plate. The sole piece A is shaped on top to conform to the shape of the boot-sole; but I preferably steam and bend it upward, so that when applied it will require some force to press it out.

Its elasticity causes it to yield to this force, and to clamp firmly the sole, to which it is held by a simple rubber across the instep, or by any light fastening like that marked *c c* in the drawing. This auxiliary plate is beveled on the edges, so as to render it scarcely visible to persons other than the wearer without a close inspection. The heel part is made separate, and in any suitable way, so as to conform to the depth and shape of the boot-heel. The heel part B is shown in drawing cut out of the wood so as to have the side *a* in addition to the bottom. *b* is a lug on the hinder part of the heel piece, to prevent any tendency of the foot to slip backward.

Having thus described all that is necessary to a full understanding of my invention, what I claim as new, and desire to protect by Letters Patent, is—

As a new article of manufacture, the detachable wooden sole A B having the form shown, and provided with the straps *c c*, the whole being arranged and adapted to the purpose set forth, in the manner specified.

ROBERT JOHNSTON.
